UNITED STATES PATENT OFFICE

ANTON J. YEAGER, OF WISCONSIN RAPIDS, WISCONSIN, ASSIGNOR TO PRENTISS WABERS PRODUCTS CO., OF WISCONSIN RAPIDS, WISCONSIN, A CORPORATION OF WISCONSIN

CAMP STOVE

Application filed April 6, 1925. Serial No. 20,903.

This invention relates to a new and improved stove construction, and more particularly to a construction of liquid fuel types of stoves of forms which are collapsible, in order to render them readily portable. Stoves of this character, in general, comprise a housing, one or more burners, a fuel tank and connecting piping between the fuel tank and burners. It is customary to have such a connection between the fuel tank and burner assembly as to permit the tank to be placed within the housing for purposes of transport and to be placed outside of the housing when in use. This is desirable since it permits a wall of the housing to be between the tank of inflammable fuel and the flame from the burners. In usual types of construction this result is obtained by disconnecting the tank from the burner assembly when placing the tank in the housing. This is undesirable, since it makes the tank a disconnected element which may become displaced or lost and also because it involves a loose connection in the fuel piping which may leak or become disconnected during the use of the stove.

It is an object of the present invention to provide a stove construction in which the tank is permanently connected to the burner assembly, and in which the tank may be moved into and out of the housing.

It is a further object to provide a construction of this character, in which the burner assembly is permanently connected to the housing.

It is also an object to provide a construction in which the connection between the burner assembly and housing is adapted to permit displacement of the assembly relative to the housing such as to enable the tank to be lifted over a wall of the housing in moving it from one position to another.

It is an additional object to provide a construction of this character, which is composed of but few and simple parts and adapted for rapid commercial production.

Other and further objects will appear as the description proceeds.

I have illustrated certain preferred embodiments of my invention in the accompanying drawings, in which

Figure 1 is an elevation of one form of construction, certain portions being broken away;

Figure 2 is a plan view taken on the line 2—2 of Figure 1;

Figure 3 is a view similar to Figure 1, but showing the parts in the traveling position;

Figure 4 is a section taken on the line 4—4 of Figure 2;

Figure 5 is a fragmentary view showing the fuel valve construction, and

Figure 6 is a view similar to Figure 1, but showing a modified form of construction.

Referring first to the form of construction shown in Figures 1 to 5, the burner assembly 11 is carried within the housing 12. This housing 12 is provided with a hinged lid 13, with wind breaks 14 hingedly connected to the lid and with the pivoted supporting legs 15. The housing is also provided with the grate 16 which is pivotally connected to the housing and which rests on the flange members 17 and 18.

The fuel pipe 19 is connected at one end to the needle valve 20, which latter is secured to the fuel tank 21. The pipe 19 is also secured to the burners 22 and 23 by means of the clips 24 and 25 and its end 26 is located so as to discharge into the lower portion of the burner assembly 11. The burner assembly is provided with the connecting pin 27, to the ends of which are secured the links 28. The links 28 are pivotally connected to the links 29, the opposite ends of which are secured to the member 30, which latter is secured to the bottom of the housing 12.

The tank 21 has secured thereto the hooks 31, the upper ends of which are adapted to engage an edge of the housing when the stove is in operating position. As shown in detail

in Figure 5, the needle valve 20 is provided with the handle 32 by which the flow of fuel from the tank 21 to the pipe 19 may be controlled. The intake pipe 33 of the valve extends down close to the bottom of the tank 21.

5 As shown in Figures 2 and 6, the tank 21 is provided with a valve fitting 34 by means of which fuel may be placed in the tank. Also, this fitting permits air under pressure to be forced into the tank above the fuel, so as to force the fuel to pass up through the pipe 33 and pass the valve 20 and through the pipe 19 to the burners.

10 The form of construction shown in Figure 6 differs from that previously described only in the means of connection between the burner assembly 11 and housing 12 and in the construction and the connection of the fuel pipe. In this form of construction the burner assembly 11 has connected thereto a pair of links 35, the opposite ends of which are connected to the member 36, the latter member being secured to the bottom of the housing. The pipe 37 connects the tank and burner assembly and is held upon the top of burners 22 and 23 by clips 38 and 39. These clips 38 and 39 somewhat loosely engage the pipe 37 so that it may be moved longitudinally relative to the burners.

15 20 The position of the tank 21 when traveling is indicated in broken lines at 21'. The position of the inner end of pipe 37 when traveling is indicated at 37' by broken lines. The burner assembly and link are in the same position when traveling and when the stove is in use. They are moved from this position only when moving the tank and connecting piping from working to traveling position and vice versa.

25 30 In moving the parts of the form of construction shown in Figures 1 to 5 from the traveling position shown in Figure 3 to the working position shown in Figure 1, it is merely necessary to lift the burner and tank assembly until the tank clears the upper edge of the side of the housing to move it laterally until the hook members 31 are located approximately above the edge of the housing and to lower it until the hooks engage the housing edge. The bottom of the burner assembly will then rest against the member 30 inside of the housing, as clearly shown in Figure 1. To restore the parts to traveling position, the burner and tank assembly is lifted, moved to the right and lowered to the position shown in Figure 3. These movements are limited and guided by the links 28 and 29 which permanently secure the parts together. It will be understood that during these movements of the burner and tank assembly it will be necessary to swing the lid or cover 13, the wind breaks 14 and the grate 16 up out of the way of the movement.

35 In moving the parts of the form of construction shown in Figure 6 from the travel-

ing position shown in broken lines to the operating position showing full lines, the left or tank end of the assembly is swung upwardly, so that the tank may clear the edge of the housing 12 and the tank is moved to the left away from the burner assembly until it may be lowered to bring the hooks 31 into engagement with the upper edge of the housing wall. This lateral movement of the tank is permitted by the sliding connection between the pipe 37 and the clips 38 and 39. In restoring the parts to traveling position, the tank end is swung up until the tank may be moved to the right and then lowered into the housing. During this movement, the pipe 37 slides to the right relative to the clips 38 and 39 and the burners 22 and 23.

40 It will be understood that in the use of the stove the tank 21 is filled with gasoline or similar fuel through the filling opening closed by cap 34. Air under pressure is then forced into the tank above the fuel. To start up the stove the valve 20 is opened by means of handle 32, and the air pressure forces the fuel past the valve and through the pipe 19. It drips into the heating pan 40, and, when a small amount has accumulated therein, it is ignited and serves to heat part of the pipe 19 and the burner 23. The gas in the pipe is thus vaporized by heat and passes out of the pipe 19 into the burner assembly in the form of vapor and then up through the assembly to the burner 23 where it is ignited. During the use of the stove the heat from the burners vaporizes the fuel in the pipe passing over them and none of the fuel enters the pan 40. The burner 22 is controlled by valve 41.

45 50 The supply pipe 33 extends nearly to the bottom of the tank 21 and therefore practically all of the fuel in the tank can be forced out by the air above it. The fuel leads from the pipe 19 at a level below that of the normal fuel level in the tank and the siphon action assists the flow of the fuel. The fuel enters the burner assembly from below and rises to the burners and its movement is assisted by the normal upward movement of the heated gases.

55 60 While I have illustrated certain preferred embodiments of my invention, it is to be understood that I contemplate such further changes and modifications as come within the spirit and scope of the accompanying claims.

I claim:

65 70 1. A stove construction comprising a housing, a burner assembly in said housing, a fuel tank, and means permanently connecting the tank and burner assembly, such means permitting a limited linear displacement of the tank relative to the burner assembly to permit the tank to be placed inside or outside of the housing.

75 80 2. A stove construction comprising a housing, a burner assembly, a tank permanently secured to the burner assembly, and an ar-

ticulated connection between the burner assembly and tank and the housing, whereby the burner assembly may be displaced jointly to permit placement of the tank in or out of the housing.

5 3. A stove construction comprising a burner assembly, a tank and rigid means connecting the assembly and tank, the tank and assembly having an operative position relative to each other in which fuel may pass from the tank to the assembly, the rigid means connecting the tank and assembly permitting a slideable adjustment between the assembly and tank between the operative position and an inoperative position, and means for limiting said adjustment.

10 4. A stove construction comprising a burner assembly, a tank, a pipe connected to the tank, a slideable rigid connection between the pipe and the burner assembly, the tank and assembly having an operative position where fuel may pass from the tank through the pipe to the assembly, and means limiting the slideable movement at operative and inoperative positions and preventing separation of the pipe and burner assembly.

15 5. A stove construction comprising a burner assembly, a tank, a pipe connected to the tank, the pipe extending across the top of the burner assembly, rigid means permanently connecting the pipe to the assembly, the tank and assembly having an operative position wherein the pipe makes connection for the passage of fuel from the tank to the burner assembly, the rigid connecting means permitting a sliding movement between the pipe and top of the burner assembly between operative and inoperative positions and retaining the pipe across the top of the burner assembly throughout said range of movement.

20 6. A stove construction comprising a housing, a burner assembly, a tank, means slidably connecting the tank and assembly, and an articulated connection between the assembly and housing whereby the assembly and tank may be jointly moved relative to the housing to permit placement of the tank internally or externally of the housing.

25 7. A stove construction comprising a housing, a burner assembly, a tank, a pipe connected to the tank, the pipe extending across the top of the burner assembly, means slidably connecting the pipe to the assembly, and an articulated connection between the assembly and housing whereby the assembly may be tilted relative to the housing to permit placement of the tank internally or externally of the housing.

30 8. A stove construction comprising a housing, a burner assembly, a tank, a pipe connected to the tank, the pipe extending across the top of the burner assembly, means slidably connecting the pipe to the assembly, and an articulated connection between

the assembly and housing whereby the assembly may be moved relative to the housing to permit placement of the tank internally or externally of the housing, and links connecting the burner assembly to the bottom of the housing whereby the burner assembly may be tilted relative to the housing to permit the tank to be slid into or out of the housing.

70 Signed at Wisconsin Rapids, Wisconsin, 75 this 3rd day of April, 1925.

ANTON J. YEAGER.
